UNITED STATES PATENT OFFICE.

JOHN GRAF, SR., OF MILWAUKEE, WISCONSIN.

DESIGN FOR A BOTTLE.

Application filed July 31, 1924. Serial No. 10,331. Term of patent 14 years.

To all whom it may concern:

Be it known that I, JOHN GRAF, SR., a citizen of the United States, residing at 901 Greenfield Avenue, Milwaukee, in the county of Milwaukee and State of Wisconsin, have invented a new, original, and ornamental Design for Bottles, of which the following is a specification, reference being had to the accompanying drawing, forming part thereof.

Figures 1 and 2, respectively, are a front and a back view of a bottle showing my new design.

I claim:

The ornamental design for a bottle, as shown.

JOHN GRAF, SR.
